ATTACHABLE CUFF FOR TROUSER LEGS
AND THE LIKE

Charles Crompton, Jr., Brooklyn, N. Y.

Application August 7, 1951, Serial No. 240,678

3 Claims. (Cl. 2—232)

1

This invention relates to detachable cuffs for trouser legs or jacket or shirt sleeves. It is particularly directed to a detachable cuff which will fit over the original cuff or substitute for it completely.

An object of this invention is to provide a highly improved detachable cuff of the character described which may be detachably attached to the lower end of the trouser leg, thereby saving wear on the original trouser cuff and prolonging the life of a pair of trousers or a suit of clothes, and which shall be provided with means to keep said additional cuff smooth and neat in appearance.

Yet another object of this invention is to provide a detachable cuff of the character described, of novel shape and color, to add new style to sport clothes, thereby causing greater interest in the appearance and style of trousers.

Yet another object of this invention is to provide a detachable cuff of the character described provided with spring clips for detachably attaching the cuff to the lower end of the trouser leg, and for keeping the added cuff smooth and flat and of pressed appearance.

Yet a further object of this invention is to provide a detachable cuff of the character described which shall be inexpensive to manufacture, easy to attach and detach, which shall be durable, attractive in appearance, and yet practical and efficient to a high degree in use.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims.

In the accompanying drawings in which are shown various illustrative embodiments of this invention,

Fig. 1 is a side elevational view of the lower end of a trouser leg showing a detachable cuff embodying the invention attached to the original trouser leg cuff, and with parts broken away;

Fig. 2 is a cross-sectional view taken on line 2—2 of Fig. 1;

Fig. 2A is a side elevational view of the clip 19 shown in Fig. 2 but removed from the cuff and trousers;

Fig. 3 is a view similar to Fig. 2 but illustrating a modified construction;

Fig. 4 is a side elevational view of one of the spring clips employed in the modification shown in Fig. 3;

2

Fig. 5 is a view similar to Fig. 2 and illustrating yet another modified construction;

Fig. 6 is a cross-sectional view similar to Fig. 2 but illustrating yet another modified construction;

Fig. 7 is also a view similar to Fig. 2 but illustrating yet another modification.

Referring now in detail to the drawing, 10 designates a trouser leg provided with the usual cuff 11. The cuff 11 comprises an upturned double layered folded portion 12 forming a fold 13 at the bottom and having a folded edge 14 at its upper end. In the drawing, 15 designates a detachable cuff embodying the invention, detachably attached to the original cuff 11.

The cuff 15 comprises a tubular sleeve 16 of cloth, synthetic plastic sheeting or any other suitable flexible sheet material. The tubular sleeve 16 may increase in height either towards its front 10 end or rear end, as shown in Fig. 1. Thus in Fig. 1 the tubular sleeve 16 is higher at one end 17 than at the other end 18, having an inclined upper edge. The tubular sleeve 16 may be of equal height throughout, if desired, or it may have 20 any other suitable ornamental shape.

Within the sleeve 16, at each side of the trouser leg, are a pair of spring clips 19 and 20. The spring clips 19 and 20 are similar except that one clip may be longer than the other to conform to the height of the cuff sleeve 16. Only one spring clip 19 will therefore be described.

Each spring clip 19 comprises a lower torsion spring 21. The torsion spring 21 has a pair of arms 22 and 23. Attached to one arm 22 is a plate 24. Attached to the other arm 23 is a plate 25. The plate 25 extends upwardly to a greater height than the plate 24. At the upper end of the plate 25 is a coil torsion spring 26 having one arm 27 attached to the upper end of said plate. 30 Attached to the other arm 28 of the torsion spring 26 is a downwardly extending plate 29. The torsion spring 21 may be wider than the torsion spring 26.

Plate 25 may be formed with openings 30 for the purpose hereinafter appearing, and plate 24 is formed with openings 31 for the purpose hereinafter appearing.

The sleeve 16 has a portion 35 contacting the outer surface of plates 24. Extending downwardly from portion 35 is a fold portion 36 wrapped around the undersides of the springs 21. Extending upwardly from portion 36, is a portion 37 contacting the outer surfaces of plates 25. Extending from the upper end of portion 37 is 50 a portion 38 wrapped around the springs 26. Extending down from portion 38 is a portion 39

contacting the outer surfaces of plates 29. At the lower end of portion 39 is a fold portion 40 wrapped around the lower edges of plates 29. Extending upwardly from fold 40 is a portion 41 contacting the inner surfaces of plates 29. At the upper end of portion 41 is a fold edge 42 located below the springs 26. Extending down from the fold 42 is a portion 43 contacting the inner surfaces of plates 25. At the lower end of portion 43 is a folded up portion 44 located above the spring 21. Extending upwardly from fold portion 44 is a portion 45 contacting the inner surfaces of plates 24. At the upper end of said portion 45 is a fold portion 46 folded over the upper edges of plates 24 and interconnecting portions 45 and 35. The portion 45 of sleeve 16 contacts the inner surface of the trouser leg adjacent its lower end. The fold 45 folds around the lower fold 13 of the trouser leg. Portion 43 contacts the outer surface of the cuff 12. The fold 42 folds around the fold 14 of the cuff 12. The portion 41 contacts the inner surface of the cuff 12. The portion 39 contacts the outer surface of the trouser leg.

It will now be understood that the coil springs 21 tend to press plates 24 towards plates 25 for clamping a portion of the sleeve 16 against the lower end of the trouser leg. Also, the coil springs 26 press plates 29 towards plates 25 for gripping the upper end of the trouser cuff 12.

The portion 37 of the sleeve 16 is stitched by means of stitching 50 to plate 25, said stitching passing through the openings 30. Furthermore, the portion 35 of the sleeve 16 is stitched to plate 24 by means of stitching 51 passing through the openings 31. Thus the sleeve 16 is held in stretched or taut and smooth condition around the cuff of the trouser leg. The additional cuff 15 may be readily attached and easily removed from the trouser leg cuff and protects the same. The sleeve 16 may be of different color to add to the styling, if desired.

Furthermore, the additional cuff 15 instead of comprising a completely tubular sleeve 16 may have the parts 40, 41, 42, 43, 44, 45 and 46 omitted, so that it comprises a sleeve or band of cloth or other flexible sheet material.

In Fig. 3 there is shown a trouser cuff 15a embodying the invention and illustrating a modified construction. The trouser cuff 15a is likewise detachably attached to the trouser leg 10 and its cuff 11. The additional cuff 15a comprises a band or sleeve-like piece of cloth or other flexible sheet material 16a held in place by four spring clips 60 (Fig. 4) two on one side of the trouser leg and two on the other.

Each spring clip 60 comprises a coil torsion spring 61 to one arm of which is attached an upwardly extending plate 62 formed with a downwardly extending punched out spring tongue 63. Attached to the other arm of the spring 61 is a plate 64. The upper end of plate 64 is attached to one arm of an upper torsion spring 65, to the other arm of which is attached a downwardly extending plate 66 formed with a punched out upwardly extending tongue 67.

The sleeve 16 has an inner portion 70 contacting the outside surfaces of plates 62 and the upper edge of said portion 70 is received between the tongues 63 and plates 62, so as to be gripped thereby. Extending from portion 70 is a fold portion 71 wrapped around the torsion springs 61.

Extending from portion 71 is a portion 72 contacting the outer surfaces of plates 64. At the upper end of portion 72 is a top fold portion 73

folded around the upper torsion springs 65. Extending downwardly from the fold portion 73 is a portion 74 contacting the outer surfaces of plates 66. The lower edge of portion 74 is received between the upwardly extending spring tongues 67 and said plates 66 so as to be gripped thereby.

At the inner surface of plate 70 of each spring clip 60 is a rough pronged gripping portion 75 to aid in gripping the cloth of the trouser leg.

It will now be understood that the spring 61 compresses plate portions 62 and 64 together, gripping the lower end of the trouser leg. Such gripping or clamping engagement is enhanced by the gripping portion 75. It will also be understood that the torsion spring 65 clamps plates 66 and 64 together to grip the portion 12 of the cuff 11. Thus the additional cuff 15a covers the original cuff of the trouser leg and protects it, and thus extends the life of the trousers and hence of the whole suit. Furthermore, this additional cuff may be made of ornamental material and adds to the attractiveness or style of the garment.

In Fig. 5 there is shown a protective cuff 15b attached to the lower end of a cuffless trouser leg 16a. The cuff 15b comprises a band or sleeve 16b of cloth or other flexible sheet material, held in place, likewise, by four spring clips 80, only one of which will be described herein.

Two of the spring clips are located on each side of the trouser leg. Each spring clip 80 comprises a plate 81 formed with a punched out downwardly extending spring tongue 82. Attached to the lower end of plate 81 is one arm of a coil torsion spring 83. The other arm of the torsion spring 83 is attached to the lower end of a plate 84 formed with a punched out upwardly extending spring tongue 85.

The sleeve 16b comprises a portion 86 contacting the outer surface of plate 81. The upper edge of said portion 86 is gripped between the tongue 82 and said plate 81. Extending from said portion 86 is a bottom fold portion 87 folded around the lower ends of the spring clips. Extending upwardly from portion 87 is a portion 88 contacting the outer surface of plate 84. At the upper end of portion 88 is a top fold portion 89 folded around the top edge of plate 84. Extending from said top fold portion 89 is a portion 90 gripped between the tongue 85 and said plate 84. Plate 80 may have indented prongs 91 to aid in gripping the trouser leg.

It will now be understood that the torsion spring 83 serves to clamp plates 81 and 84 together to grip the lower end of the trouser leg, and such grip is aided by the gripping portion 91.

In Fig. 6 there is shown a trouser leg 10 provided with a cuff 11. Detachably attached thereto is an additional protective cuff 15c embodying the invention and illustrating another modified construction. The trouser cuff 11 has an upwardly extending portion 12, as shown in the drawing. The additional cuff 15c comprises likewise a plurality of spring clips 100 attached to a band or sleeve 16c of cloth or other suitable flexible sheet material. Each spring clip 100 comprises a plate 101 having an inwardly extending prong 102 at its upper end. At the lower end of plate 100 is a coil torsion spring 103. Attached to the torsion spring 103 is an upwardly extending plate 104 connected to one arm of a torsion spring 105. The other arm of the torsion spring 105 is attached to a plate 106 extend-

ing downwardly and formed at its lower end with an inwardly extending prong 107.

The sleeve 16c has a portion 106 contacting the outside surface of plate 101 and stitched thereto by stitching 107a passing through openings in the plate 101. Extending from said portion 106 is a bottom fold portion 108 folded around the lower end of the spring clip. Extending upwardly from the bottom fold portion 108 is a portion 109 contacting the outer surface of plate 105 and stitched thereto by stitching 110a passing through suitable through openings in said plate 104. At the upper end of portion 109 is a top fold portion 110 folded around the upper end of the spring clip. Extending downwardly from the top fold portion 110 is a downwardly extending portion 111 contacting the outside of plate 106 and stitched thereto by stitching 112 passing through suitable openings in said plate.

It will now be understood that the spring 103 presses the plates 101 and 104 together to cause the prong 102 to grip the trouser leg. Also, the torsion spring 105 presses plate 106 towards plate 104 to cause the prong 107 to grip the cuff portion 12.

In Fig. 7 there is shown a trouser leg 10 provided with cuff 11 having an upwardly turned cuff portion 12. In said figure is also shown an additional cuff 15d illustrating yet another modified construction and comprising a band or sleeve 16d of cloth or other suitable flexible sheet material, attached to a plurality of spring clips 120, one of which is shown also in Fig. 8.

Each spring clip 120 comprises a plate 121 formed with a punched out downwardly extending spring tongue 122. Riveted or otherwise attached to the lower end of plate 121 is a plate 123 formed adjacent its upper end with a downwardly extending punched out tongue 124. The tongue 124 is formed with a punched out upwardly extending tongue 124a for the purpose hereinafter appearing.

The sleeve 16d comprises a plate 125, the upper end of which is gripped between the tongue 122 and the plate 121. Extending from portion 125 is a bottom fold portion 126 wrapped around the lower edge of the spring clip 120. Extending upwardly from the bottom fold portion 126 is a portion 127 contacting the outer surface of plate 123. At the upper end of portion 127 is a top fold portion 128 folded about the upper edge of plate 123. Extending downwardly from the top fold portion 128 is a portion 129 gripped between the spring tongue 124a and the spring tongue 124. The lower end of the trouser leg cuff is gripped between the plate 120 and the plate 123 by the spring action of said plates. The upper end of the cuff portion 12 is gripped between the spring tongue 124 and the plate 127. Thus the clips are firmly gripped to the trouser leg and the

sleeve 16d is firmly gripped to the spring clips.

Any suitable number of said spring clips may be employed in any of the modifications described herein.

5 It will thus be seen that there is provided a device in which the several objects of this invention are achieved and which is well adapted to meet the conditions of practical use.

As various possible embodiments might be 10 made of the above invention, and as various changes might be made in the embodiment above set forth, it is to be understood that all matter herein set forth or shown in the accompanying drawings is to be interrupted as illustrative and 15 not in a limiting sense.

Having thus described my invention I claim as new and desire to secure by Letters Patent:

1. In combination with a trouser leg having 20 an upturned cuff, an additional cuff comprising a plurality of spring clips and a band of flexible sheet material and means to attach said band to said clips, each of said clips comprising a lower spring clamp to clamp the lower fold of said upturned cuff, and an upper spring clamp to clamp the upper edge of said upturned cuff, and said band of flexible sheet material comprising a portion disposed at the inside of the trouser leg, and portions covering said clips and the outside of said upturned cuff and the upper edge of said upturned cuff.

2. A cuff to be detachably secured to the cuff 25 of trousers, comprising a clip having spring means to grip the top of the trouser cuff, and spring means to grip the lower end of the trouser and its cuff, a band of flexible material encircling the trouser cuff, and completely covering the clip, and means to attach said band to said clip.

3. A cuff to be detachably secured to the cuff 30 of trousers, comprising a clip having a plate, spring means to grip the top of the trouser cuff, and spring means to grip the lower end of the trouser and its cuff, a band of flexible material encircling the trouser cuff, and completely covering the clip, and means to attach said band to said clip, and said spring means to grip the lower edge of the trouser comprising a torsion spring having two arms, said spring means to grip the top edge of the trouser cuff comprising a torsion spring having two arms and one arm of 35 each of said torsion springs being interconnected by means of said plate.

CHARLES CROMPTON, JR.
